United States Patent Office

Des. 178,008
Patented June 12, 1956

178,008

WATCH OR SIMILAR ARTICLE

Henry Pommier, New York, N. Y.

Application September 30, 1955, Serial No. 38,187

Term of patent 7 years

(Cl. D42—8)

Fig. 1

Fig. 2

Fig. 3

Fig. 1 is a plan view of a watch or similar article showing my new design.

Fig. 2 is a front perspective view thereof.

Fig. 3 is the opposite side of that shown in Fig. 2.

I claim:

The ornamental design for a watch or similar article, substantially as shown.
